UNITED STATES PATENT OFFICE.

JOSEPH B. ELKER AND PETER J. JACOBS, OF PITTSBURG, PENNSYLVANIA.

CURTAIN-POLE.

SPECIFICATION forming part of Letters Patent No. 601,372, dated March 29, 1898.

Application filed April 10, 1897. Serial No. 631,641. (No model.)

To all whom it may concern:

Be it known that we, JOSEPH B. ELKER and PETER J. JACOBS, citizens of the United States, residing at Pittsburg, in the county of Allegheny and State of Pennsylvania, have invented certain new and useful Improvements in Curtain-Poles; and we do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to certain new and useful improvements in curtain-fixtures.

The invention has for its object the provision of a means whereby the curtain-pole may be raised and lowered for the purpose of 20 removing from and replacing the curtain, thereby overcoming the necessity of having to mount upon a chair or ladder.

With the above and other objects in view the invention finally consists in the novel construction, combination, and arrangements of parts, as will be hereinafter more specifically 25 described in detail.

In describing the invention in detail reference is had to the accompanying drawings, 30 forming a part of this specification, and wherein like figures of reference designate like parts, in which—

Figure 1 is a front view of the device as it is applied to the window-frame. Fig. 2 is a 35 side view of the same. Fig. 3 is an enlarged front view of the extension-rod. Fig. 4 is a side elevation of the brackets. Fig. 5 is a front view of the bracket. Fig. 6 is a plan view of the bracket. Fig. 7 is an enlarged end 40 sectional view through the extension-rod on the line A B of Fig. 3. Fig. 8 is a vertical section on the line x x of Fig. 3 on an enlarged scale.

Referring to the drawings, the numerals 1 45 and 1' designate a rod formed of two separate parts or sections. The inner end portion of each section is cut down in a semicircular form, or "halved," so that when they are placed together they will form a rod of the 50 same diameter at all parts. At or near the

inner ends of each of the said sections are secured the collars 2 and 2', which act as guides or "keepers" when the rod is extended out to various lengths for window-frames of different widths, as well as various-lengthed poles. 55 3 and 3' are cylindrical boxes which contain suitable spring-actuated reels 10 and 10' and to which the supporting tapes or cords 4 and 4' are attached. Arranged upon the curtain-pole 5 are the straps 9 and 9', which form a 60 means whereby the said pole is attached to the supporting tapes or cords. A pair of brackets 6 and 6' are suitably attached to the window-frame at a convenient point. Upon each of the said brackets is attached the upwardly 65 extended and adjustable lug-pieces 7 and 7', which are adapted to form bearings for the support of the extension-rod.

To remove the curtain from the pole, the curtain is grasped at the lower end and pulled 70 down until the pole is in a convenient position for the removal of the curtain, and when in such position it may be held by any suitable means. After replacing the curtain the pole is released and allowed to ascend to its former position by the action of the spring-reels and tapes.

Having thus fully shown and described our invention, what we claim as new, and desire to secure by Letters Patent, is— 80

In a curtain-fixture the combination with the brackets comprising the vertical portions, and the horizontal portions formed with slots, the laterally-adjustable bearings seated on said horizontal portions, the set-screws passing through said slots and engaging with the said bearings, the extensible rod made in two semicylindrical overlapping sections, with cylindrical outer ends, and the movable collars, of the boxes, the spring-actuated reels, 85 the straps connected therewith and the curtain-pole also connected with said straps, substantially as described.

In testimony whereof we affix our signatures in presence of two witnesses.

JOSEPH B. ELKER.
PETER J. JACOBS.
